CLAIM

The ornamental design for a photoconductor unit for forming an image, as shown.

DESCRIPTION

FIG. 1 is a right side elevational view of a photoconductor unit for forming an image;

FIG. 2 is a left side elevational view of a photoconductor unit for forming an image;

FIG. 3 is a top plan view of a photoconductor unit for forming an image;

FIG. 4 is a front elevational view of a photoconductor unit for forming an image;

FIG. 5 is a bottom plan view of a photoconductor unit for forming an image;

FIG. 6 is a rear elevational view of a photoconductor unit for forming an image; and,

FIG. 7 is a top, front and left side perspective view of a photoconductor unit for forming an image.

FIG. 1**FIG. 2****FIG. 3****FIG. 4****FIG. 5****FIG. 6****FIG. 7**
